UNITED STATES PATENT OFFICE.

T. CLARENCE HEISEY, OF NEWARK, OHIO, ASSIGNOR TO A. H. HEISEY & CO., OF NEWARK, OHIO.

DESIGN FOR A GOBLET.

Application filed May 8, 1920. Serial No. 379,983. Term of patent 3½ years.

To all whom it may concern:

Be it known that I, T. CLARENCE HEISEY, a citizen of the United States, residing at Newark, county of Licking, and State of Ohio, have invented a new, original, and ornamental Design for a Goblet, of which the following is a specification.

I claim:

The ornamental design for a goblet as shown.

T. CLARENCE HEISEY.
